Inventor:

Ralph P. Cummings

UNITED STATES PATENT OFFICE.

RALPH P. CUMMINGS, OF SOUTH PORTLAND, MAINE.

STROPPING MACHINE.

Application filed February 27, 1922. Serial No. 539,707.

To all whom it may concern:

Be it known that I, RALPH P. CUMMINGS, a citizen of the United States, residing at South Portland, in the county of Cumberland and State of Maine, have invented new and useful Improvements in Stropping Machines, of which the following is a specification.

My invention relates to that class of machines into which a so called "safety" razor blade may be inserted and by a movement to and fro over the surface of a strop whet or sharpen same until a keen "edge" is produced.

In my mechanism the blade is so presented to the surface of the strop as to get a whetting action partly cross-wise and partly length-wise of the cutting beveled edge. I have demonstrated that I can produce a keener cutting blade by this method.

By referring to the drawing accompanying this specification the design and principle of construction can be clearly seen. In Fig. 1, I show, in perspective, the assembled device, with the blade inserted in the holder, and outline of strop in dot and dash lines; Fig. 2 is a view, in perspective, of a part of the blade holder, showing a blade partly inserted in same; Fig. 3 is a plan view of the complete machine; Fig. 4 is a side view, taken from the side on which is the rack and pinion gear, and Fig. 5 is a sectional view taken on line $x-x$, Fig. 3.

Similar numerals refer to similar parts throughout the several views.

Pivotedly mounted on a base plate 1, and turning about screw pin 2, is a flat bar 3 with upturned ends 4, 4, in holes 5, 5, in which, rotates rod 6. On this rod 6 is riveted or otherwise secured a blade holder 7, in the bifurcated edge of which can be inserted a safety-razor blade in its own mounting, as seen at 8. The two outwardly projecting bifurcations, or as I may term them, plates, of which holder 7 is partly composed, are seen at 7', and in assembling this holder, these plates are slightly sprung together, thus tending to hold the blade, within its mounting, with a slight frictional grip. The angular action or pull on the blade when the machine is in operation drives it up firmly against the collar 9, which prevents further end movement to the blade. Beads over edges of plates 7, 7', prevent the blade

mount from pulling out of the holder while the machine is sliding along the surface of the strop.

A guard 10 is secured to the top of bar 3, directly beneath the blade holder 7, two side edges 11, of which guard extend outwardly and upwardly, but are shortened sufficiently so that their bearing on the under side of the strop will not be directly under the bearing point or surface of the edge of the blade where it contacts with the strop, as seen by reference to Fig. 5. It will thus be observed that a very supple and resilient contact of the blade with the strop may be obtained, while at the same time a dependable support is provided for both. On the over-hanging end of bar 3 is a vertical handle or post 12, for operating the machine.

Opposite the operating end of bar 3, and mounted rigidly on rod 6, is a segmental gear 13, adapted to operate in circular rack 14, cut on over-extending edge of base plate 1. While I have described this as one method of imparting rotary movement to rod 6, I do not confine myself specifically to this design, as any practical combination of cams and levers which will accomplish my purpose may be substituted.

On both ends of the base plate 1 are fenders 15, extending upwardly from the floor of the plate and having securely fixed in each, rods 16, which extend across the space between sides 15, 15. At 17 is shown the extreme ends of the base plate bent upward to form friction guards. By reference to Fig. 5 it will be seen that the strop 18 does not have a perfectly free movement between rod 16 and guard 17, or in other words there is a slight tendency to retard the free and uninterrupted travel of the machine over the strop, the reason for providing which feature to be hereinafter made clear.

In Fig. 4 the position assumed by the blade, gear and other parts is such as would take place by the movement of the bar 3 to central position, or on line $y-y$, Fig. 3. There are also seen in Fig. 3 the two extreme positions of the movable parts of my machine. Parts shown in full lines would move in the direction of the arrow, shown in full lines; and contra-wise for dotted parts. The blade upon which the stropping has been completed may be detached from the

machine by pulling out of the holder, length-wise of the slot, and another blade inserted by reversing the process.

Now in operation, the user grips the post 6 12 and pulls or pushes, depending on which end of the strop the machine may be located. In Fig. 3 we will assume that the machine has just reached the extreme right hand end of the strop (holder shown in full lines). It 10 might appear at first glance that a backward pull (or to the left as seen in drawing) of the handle would force the blade into the strop. Such, however, is not the case; what happens is this: The slight frictional 15 resistance of the machine over the strop, where the latter passes between rod 16 and guard 17, and to which reference has heretofore been made, is sufficient to hold the body of the machine on the strop while pulling 20 the post or handle 12 from the position at A to the position at B. It is, in other words, a slip movement, and there is no tendency whatever for the blade to become imbedded in the strop when reversing the direction of 25 movement. The slightest action of post 12 starts gear 13 into action with rack 14, and as the former is rigidly secured to shaft 6, which is in turn secured to holder 7, the blade will start upward from the strop on 30 the first movement of gear 13, and until it has taken an extreme opposite position on the base plate, no movement of the machine forward can be made.

The tension of the blade on the strop constitutes a stop to pull or push the machine backward or forward and is in proportion to the amount of force applied to post 12 in a turning action around pivot pin 2. As 35 stated in the preamble, the stropping is a combination of cross-wise and length-wise 40 whetting of the blade on the strop. The blade is placed at an angle with the strop and without change of this angle is drawn over the length of the strop. The other side,

on the reverse movement, is treated like- 45 wise. Then by removing the blade from the holder and reinserting it with the ends re- versed a cross whetting is obtained.

This accomplishes what draw and cross filing does to a piece of steel—where the 50 cross filing marks show up, the draw filing will smooth them off. The action of my machine gives a better edge to the razor, polishes the bevel by cross-whetting, taking out the minutest abrasions, and with the 55 same length of blade does not require as wide a strop in operation.

Having thus described my invention, I claim:

A stropping machine comprising a base 60 member slidably mounted on a strop and having an arcuate rack thereon, a frame pivotally mounted on said base member and adapted to be swung through a part of the circumference of a circle, around a pivot, 65 an oscillating member journalled in said frame, a blade holder, adapted to hold the blade yieldingly, rigidly secured to said oscillating member, a pinion rigidly secured to said oscillating member and in mesh with 70 said rack on said base member, resilient supporting members beneath and in contact with the strop, and at a spaced distance from the cutting edge of the blade, fenders 75 on the ends of the base member to properly 80 guide the machine along the length of the strop, guards on the ends of the base member projecting upwardly for applying a slight frictional resistance to the progress of the machine along the surface of the strop, means for actuating the frame so as to place the blade in proper relation to the direction of movement of same while in the 85 operation of stropping and for moving the base and frame along the strop, substantially as described.

RALPH P. CUMMINGS.
